UNITED STATES PATENT OFFICE.

RICHARD TEICHMANN, OF BROOKLYN, NEW YORK.

TOY.

SPECIFICATION forming part of Letters Patent No. 414,265, dated November 5, 1889.

Application filed December 15, 1888. Serial No. 293,728. (No model.)

To all whom it may concern:

Be it known that I, RICHARD TEICHMANN, of Brooklyn, in the county of Kings and State of New York, a citizen of the Empire of Germany, have invented certain new and useful Improvements in Toys, of which the following is a specification.

This invention relates to an improved sheet-metal toy which can be readily moved over the floor in such a manner that the arms are alternately raised and lowered; and the invention consists of a toy the body or shell of which is supported on a roller and which is actuated by a handle-rod applied loosely to said roller, said handle-rod having an extension-wire for supporting the body. In longitudinal slots of the body are guided combined arm and leg pieces, the arms extending through the slots and being provided with offsets and guide-lugs at the inside and outside of the arms. The legs are pivoted to crank-pins at diametrically-opposite points, which latter impart a vertical reciprocating motion to the arm and leg pieces, while the body is held in upright position by the wire rod. The supporting-roller is provided with a centrally-contracted part, to which the eye-shaped portion of the handle-rod is loosely applied.

In the accompanying drawings, Figure 1 represents a side elevation of my improved toy. Fig. 2 is a vertical transverse section on line $x x$, Fig. 1, and Fig. 3 is a horizontal section on line $y y$, Fig. 1.

Similar letters of reference indicate corresponding parts.

Referring to the drawings, A represents a toy figure which is made of sheet metal and composed of three parts, a shell or body A and two combined arm and leg pieces B B, which represent the arms and legs of the toy figure, the arms b b being extended in the forward direction at right angles, or nearly so, to the middle part of the pieces B B and provided at their connection with the same with offsets b', as shown in Figs. 1 and 3, which are passed through longitudinal slots a at opposite sides of the body or shell A. The lower ends of the legs of the pieces B B

are pivoted to crank-pins d d at diametrically-opposite points, near the circumference of a roller C, which is preferably made of wood and provided with a centrally-contracted portion to which the bent eye D' of an actuating handle-rod D is applied, said roller C turning loosely in the eye of the handle-rod when pushed forward by the same on the floor. A wire D² extends in upward direction from the eye D' into the shell A of the toy figure and holds the latter in upright position on the roller C. The handle-rod D, eye D', and upright wire D² are preferably bent in one piece, the upright wire D² forming an extension of the eye of the handle-rod D.

When the toy figure is moved forward on the floor, the roller C alternately raises and lowers the combined leg and arm pieces of the toy figure by the crank action exerted by the roller on the pieces B B. The arms are guided in the slots of the toy figure by means of bent lugs f f', respectively, at the inside and outside of the shell A, as shown in Fig. 3, they imparting to the toy the appearance of a walking figure that alternately raises and lowers its arms.

As the toy consists of but few pieces, and can be cheaply manufactured, it furnishes when moved forward over the floor an entertaining and amusing toy for children, which toy can be used indoors or out of doors, as desired.

Having thus described my invention, I claim as new and desire to secure by Letters Patent—

1. The combination of a hollow body or shell having longitudinal side slots, combined arm and leg pieces, the arms of which pass outwardly through said slots, a crank-roller pivoted at opposite sides to the lower ends of the legs, and an actuating handle-rod applied loosely to the supporting-roller and provided with a rod or wire extending into the body or shell, substantially as set forth.

2. The combination of a hollow body or shell having longitudinal side slots, combined arm and leg pieces guided in said slots, the arms of said pieces being provided with offsets and interior and exterior guide-lugs

near the offsets, a crank-roller pivoted at
opposite sides to the lower ends of the legs,
and an actuating handle-rod applied loosely
to said roller and provided with a rod or wire
5 extending into the body or shell, substantially
as set forth.

In testimony that I claim the foregoing as

my invention I have signed my name in pres-
ence of two subscribing witnesses.

RICHARD TEICHMANN.
